United States Patent Office.

THOMAS R. BEARSE, OF TAUNTON, MASSACHUSETTS, ASSIGNOR TO THE
TAUNTON TACK COMPANY, OF SAME PLACE.

Design No. 3,715, dated October 19, 1869.

DESIGN FOR A TACK-HEAD.

The Schedule referred to in these Letters Patent and making part of the same.

To all whom it may concern:

Be it known that I, THOMAS R. BEARSE, of Taunton, in the county of Bristol, and State of Massachusetts, have invented a new and improved Design for a Tack-Head; and I do hereby declare that the following is a full, clear, and exact description thereof, which will enable others skilled in the art to make and use the same, reference being had to the accompanying drawings, forming part of this specification, in which the figure is a perspective view of a tack illustrating my design.

My invention has for its object to furnish an improved design for the heads of tacks, nails, &c.; and

It consists in the design herein shown and described.

A is the body of the tack, which may be made with a tack-point or with a nail-point, according to the purpose for which it is to be used.

B is the head of the tack, which is made circular in its general form, and the upper surface of which is struck up into the form of a series of four segments of pyramids, laid apex to apex around the centre of the head, as shown in the figure.

Having thus described my invention,
I claim as new, and desire to secure by Letters Patent—

The design for a tack-head, herein shown and described.

The above specification of my invention signed by me, this 22d day of September, 1869.

THOS. R. BEARSE.
